DESIGN FOR A KNIFE RACK

Albert E. Rosenberg, New York, N. Y.

Application June 17, 1946, Serial No. 130,819

Term of patent 7 years

(Cl. D44—29)

To all whom it may concern:

Be it known that I, Albert E. Rosenberg, a citizen of the United States, residing at the city of New York, in the county of Queens and State of New York, have invented a new, original, and ornamental Design for a Knife Rack, of which the following is a specification, reference being had to the accompanying drawing, forming a part thereof.

In the drawing:

Figure 1 is a front perspective view of a knife rack, with detachable supports attached, showing my new design.

Figure 2 is a front perspective view of the knife rack, with supports detached.

Figure 3 is a side elevational view showing the supports attached, the other side not shown being similar to the side shown.

I claim:

The ornamental design for a knife rack, as shown and described.

ALBERT E. ROSENBERG.
